US0D1002582S

(12) **United States Design Patent** (10) **Patent No.:** **US D1,002,582 S**
(45) **Date of Patent:** **** Oct. 24, 2023**

(54) **EARPIECE AND CHARGER CASE**

(71) Applicant: **OXIWEAR, INC.**, Arlington, VA (US)

(72) Inventors: **Shavini Fernando**, Arlington, VA (US);
George Donald Beckstein, III, Buffalo,
NY (US); **Ben Salthouse**, San Francisco,
CA (US)

(73) Assignee: **OXIWEAR, INC.**, Arlington, VA (US)

(**) Term: **15 Years**

(21) Appl. No.: **29/736,350**

(22) Filed: **May 29, 2020**

(51) LOC (14) Cl. **14-01**

(52) U.S. Cl. **D14/223; D24/169**
USPC ....

(57) **CLAIM**

The ornamental design for an Earpiece and Charger Case, as shown and described.

DESCRIPTION

FIG. 1 is a bottom view of the earpiece for the earpiece and charger case, showing the new design;

FIG. 2 is a top view thereof;

FIG. 3 is a left side view thereof;

FIG. 4 is a right side view thereof;

FIG. 5 is a front view thereof;

FIG. 6 is a rear view thereof;

FIG. 7 is a perspective view thereof;

FIG. 8 is a perspective view thereof;

FIG. 9 is a perspective view thereof;

FIG. 10 is a perspective view thereof;

FIG. 11 is a perspective view thereof;

FIG. 12 is a perspective view thereof;

FIG. 13 is a perspective view thereof;

FIG. 14 is a perspective view thereof;

FIG. 15 is a perspective view thereof;

FIG. 16 is a top view of the charger case for the earpiece and charger case, showing the new design;

FIG. 17 is a left side view thereof, the right side being visible in FIG. 19;

FIG. 18 is a front view thereof;

(Continued)

FIG. 19 is a perspective view thereof;
 FIG. 20 is a perspective view thereof;
 FIG. 21 is a perspective view thereof;
 FIG. 22 is a perspective view thereof;
 FIG. 23 is a perspective view thereof;
 FIG. 24 is a perspective view thereof;
 FIG. 25 is a perspective view thereof;
 FIG. 26 is a perspective view thereof;
 FIG. 27 is a top view of the charger case of FIG. 16, in a closed position thereof;
 FIG. 28 is a right side view thereof, the left side being visible in FIG. 30;
 FIG. 29 is a rear view thereof;
 FIG. 30 is a perspective view thereof;
 FIG. 31 is a perspective view thereof;
 FIG. 32 is a perspective view thereof;
 FIG. 33 is a perspective view thereof;
 FIG. 34 is a perspective view thereof;
 FIG. 35 is a perspective view thereof;
 FIG. 36 is a perspective view thereof; and
 FIG. 37 is a perspective view thereof.
